WIRE SHAPING AND DRAWING

Ben F. Ware, Euclid, Ohio, assignor to The Ajax Manufacturing Company, Euclid, Ohio, a corporation of Ohio

Filed Sept. 6, 1960, Ser. No. 54,260

12 Claims. (Cl. 72—205)

This invention relates to wire shaping and drawing and, as one of its objects, aims to provide a novel method and apparatus by which a shaping operation, for example flattening, and a drawing operation are performed on the wire during passage thereof through one and the same apparatus.

During the operation of wire drawing apparatus of the kind used to supply drawn wire directly to a fabricating machine, such as a cold header, it is often desirable that the drawn wire be of a noncircular cross-sectional shape but noncircular wire has a strong tendency to twist and the occurrence of such twist impedes the proper functioning of the dies of the header. The present invention satisfactorily overcomes the problem of twist and, as another of its objects, provides a novel apparatus and a novel method by which wire stock being drawn for direct feeding to a header or the like, is shaped or flattened during its passage through the apparatus by roll means associated with the drawing die.

A further object is to provide novel wire drawing apparatus of the type having longitudinally movable slide means and a drawing die movable thereby through a drawing stroke in a direction away from a grip device, and co-operating pressure rolls movable through a work stroke by the slide means for shaping or flattening the wire to the desired noncircular form.

Additionally this invention provides novel apparatus of the kind above indicated by which noncircular wire of accurate dimensional requirements, and particularly small-size noncircular wire, can be produced more reliably and satisfactorily than heretofore, and wherein the grip device, drawing die and shaping rolls are in a relatively closely spaced relation along the axis of the wire to minimize the occurrence of twist therein.

Other objects, novel characteristics and advantages of this invention will be apparent in the following detailed description and in the accompanying drawings forming a part of this specification and in which,

FIG. 1 is a side elevation of wire drawing apparatus provided by this invention and embodying means for shaping the wire to noncircular form;

FIG. 2 is a plan view of the apparatus;

FIG. 3 is an end view of the apparatus as seen from the wire-entering end thereof;

FIG. 4 is a partial longitudinal vertical section on a larger scale taken through the wire shaping and drawing means as indicated by section line 4—4 of FIG. 2;

FIG. 5 is a partial transverse vertical section taken through the shaping means as indicated by section line 5—5 of FIG. 4;

FIG. 6 is a fragmentary view showing co-operating portions of the rolls of the shaping means taken approximately as indicated by section line 6—6 of FIG. 4 but with the upper roll shown in elevation;

FIG. 7 is a fragmentary view of the drawing die and adjacent portions of the die slide taken as indicated by the directional line 7—7 of FIG. 4;

FIG. 8 is a fragmentary transverse sectional view taken on section line 8—8 of FIG. 1 and showing co-operating portions of the grip blocks of the grip device; and

FIG. 9 is a fragmentary transverse sectional view taken on section line 9—9 of FIG. 1 and showing co-operating portions of the feed rolls.

As a practical and preferred embodiment of this invention the drawings show an apparatus or machine 10 by

2

which shaping and drawing operations are performed on a wire or rod stock 11 by a shaping device 12 and a drawing die 13 during passage of the wire through the machine. The drawing machine 10 is here shown as being used in association with a fabricating machine 14, such as a cold header, to which the drawn wire 11a is supplied directly and at substantially the rate of production by the drawing machine. The wire 11 is advanced through the drawing machine 10 and fed to the fabricating machine 14 by co-operating feed rolls 15 and 16 of a feed device 17.

The wire drawing machine 10 comprises, in general, and as best seen in FIGS. 1 and 2, a frame structure 20 having a longitudinal guideway 21 thereon adjacent the top thereof, and a drawing or die-carrying first slide 22 movable in the guideway and actuatable therealong by a swingable draw lever 23. The machine 10 also comprises a grip device 24 having co-operating grip members or blocks 25 and 26 between which the drawn wire 11a passes and which operate to automatically grip the wire and hold the same against backward movement during a drawing stroke of the die 13. The drawing die 13 is mounted on the drawing slide 22 and is movable with the latter during the drawing and return strokes of such slide.

The guideway 21 is formed by laterally spaced longitudinal recesses 29 extending along the frame 20 on opposite sides of the main chamber or recess 30 thereof. The die slide 22 has lateral projections 31 received in the guideway 21 and confined therein by cover plates 32 attached to the frame 20 by suitable screws 33. The drawing slide 22 is of a conventional form having a die socket 34 in which the drawing die 13 is seated and retained as by means of a set screw 35. The body of the slide 22 is preferably hollow so as to provide a chamber 36 for holding a supply of lubricating powder or the like in adjacent relation to the drawing die 13. The die slide 22 preferably also has guide bushings 37 and 38 mounted therein on opposite sides of the die 13 and providing guide passages which are aligned with the orifice of the die.

The draw lever 23 is located in the recess 30 of the frame 20 and is swingably supported by a transverse pivot shaft 38 rockably mounted in laterally spaced bearings 39 and 40 of the frame. At the upper end thereof the draw lever 23 is provided with a forked portion 41 which straddles the drawn wire 11a and the portion of the die slide 22 containing the guide bushing 38. The forked portion 41 provides a pair of thrust arms 41a having convex portions which are rockably engageable with laterally spaced flat thrust members 42 on the adjacent end of the drawing slide 22.

The draw lever 23 is actuatable by a connecting rod 44 pivotally attached to the lower end thereof and having an operating connection with an eccentric portion 45 of a rotatable drive shaft 46. The shaft 46 extends transversely of the frame 20 and is suitably mounted in an outboard bearing projection 47 thereof. As shown in FIG. 3, the connecting rod 44 and the eccentric shaft portion 45 with which this rod is connected are located at the inner end of the drive shaft 46.

The drive shaft 46 can be driven from an available power source such as from the driving means of the fabricating machine 14 in which case the wire drawing machine 10 will be operated in a desired timed relation with the operation of the fabricating machine. In the apparatus here shown, this is accomplished by a drive chain 48 extending from the header 14 and passing around a sprocket 49 secured on the outer end of the drive shaft 46. The tightness of the chain 48 can be suitably adjusted by a chain tightening device 50 mounted on the outboard bearing 47 and having an idler sprocket 51 engaged with the chain.

The grip device 24 (see FIGS. 1 and 2) comprises a grip box 54 formed on or attached to the frame 20 and located at one end of the frame so as to be disposed between the feed roll device 17 and the drawing slide 22. The grip blocks 25 and 26 mentioned above are located in the grip box 54 in a vertically disposed relation and are wedge-shaped blocks whose tapered surfaces 55 are in a co-operating relation to corresponding tapered surfaces of upper and lower thrust blocks 56 and 57 which are located in the grip box above and below the grip blocks. Groups of antifriction rollers 58 are preferably provided in the grip device 24 and disposed between the grip blocks 25 and 26 and their associated thrust blocks 56 and 57.

The co-operating grip blocks 25 and 26 grip and hold the wire 11 against backward movement so that swinging of the draw lever 23 in a counterclockwise direction as seen in FIG. 1 will move the drawing slide 22 toward the left along the guideway 21 to thereby actuate the drawing die 13 through a drawing stroke by pushing the same over and along the wire. The return swinging movement of the draw lever 23 is produced by the connecting rod 44 during which the forked portion 41 of the lever is disengageable from the drawing slide 22. The return movement of the drawing slide 22 is produced by the pulling action of the wire 11 thereon which results from the advance feeding movement of the wire by the feed device 17. The return stroke of the drawing slide 22 is also produced or assisted by a pair of laterally spaced compression springs 59 acting against depending spring seats 60 of the slide and supported by guide rods 61 connected with such spring seats.

The feed rolls 15 and 16 of the feed roll device 17 are intermittently driven from an available power source, in this case, by a power take-off lever 64 (see FIGS. 1 and 2) secured on a projecting end portion of the draw lever rockshaft 38. The lower feed roll 16 is connected through a one-way clutch means 65 with an actuating lever 66 so as to be intermittently driven in response to swinging movement of such lever. The feed rolls 15 and 16 are here shown as connected by gearing 63 which need be provided only if the upper roll is intended to be driven also.

The drive lever 66 is connected with the power take-off lever 64 by a thrust link 67 whose connection to the power take-off lever is made through an adjusting device 68 by which the angular stroke of the actuating lever 66 can be varied as desired. When the co-operating feed rolls 15 and 16 are driven by power take-off means connected with the draw lever rockshaft 38 as explained just above, the feed rolls will be actuated in a timed relation to the functioning of the wire drawing machine 10 as well as in timed relation to the functioning of the header 14.

The shaping device 12 (see FIGS. 4 and 5) will be described next and is here shown as being located on the side of the drawing slide 22 from which the wire 11 is supplied, that is, on the entry side of the orifice of the drawing die 13. The shaping device 12 comprises a second or auxiliary slide 70 having lateral projections 71 operable in the guideway 21 of the frame 20. The shaping device 12 also comprises shaping rolls, in this case, a pair of upper and lower rolls 72 and 73 between which the wire 11 passes and by which such wire is subjected to a desired shaping or flattening operation.

In the wire drawing machine 10 here shown, the shaping operation being performed on the wire 11 is a flattening operation by which one side of the wire, in this case the top portion thereof, is flattened in advance of the drawing operation performed by the drawing die 13. The upper roll 72 of the flattening device 12 is accordingly a flat-surfaced roll, that is a cylindrical roll, whose pressure-engagement with the wire causes a flattening thereof. The upper rolls 72 is of a relatively small diameter so as to have only a small area of working contact with the wire for application of maximum working pressure there-

to and is freely rotatable by reason of it being mounted with the end portion 72a thereof received in a pair of antifriction bearings 74.

The lower roll 73 is a support roll for the wire 11 and supports the same during the flattening thereof by the upper roll 72. The lower roll 73 is of a relatively large diameter in comparison with the upper roll 72 and has an annular groove 75 in the periphery thereof for receiving the wire 11 and whose cross-sectional shape corresponds with that of the wire and, in this case, is a concave or semicircular groove in which the lower segment of the wire lies. The lower roll 73 is freely rotatable on an antifriction bearing 77 which is mounted on an eccentric portion 78 of a pivot shaft 79.

The co-operating rolls 72 and 73 of the shaping device 12 are supported by a bracket 80 which is attached to the second slide 70 by suitable screws 81. A passage 82 extending through the bracket 80 and the adjacent portion of the second slide 70 accommodates the wire 11 as it enters and leaves the bight or pass of the co-operating rolls 72 and 73. The antifriction support bearings 74 for the upper roll 72 are mounted in the bracket 80 as shown in FIG. 5, and the mounting shaft 79 for the lower roll 73 is mounted in the arms 84a of a depending forked portion 84 of the bracket 80.

The width of the pass between the co-operating rolls 72 and 73, and the pressure applied to the wire 11 for the shaping operation, can be varied to suit the size and type of wire being supplied as well as the particular configuration to which the wire is to be shaped or flattened during the shaping operation. For this purpose one of the co-operating rolls, in this case the lower roll 73, is shiftable for varying its position relative to the other roll and the wire. Therefore the mounting shaft 79 is rotatable in the arms 84a of the bracket 80 to cause the eccentric portion 78 to shift the lower roll toward or away from the upper roll 72, depending upon the direction of the pivotal movement imparted to the mounting shaft.

The pivot shaft 79 can be thus rotated by suitable actuating means, in this case, by an actuating lever 86 to which swinging movement is imparted by a link 87 connected to the outer end of the lever. The link 87 is here shown as being a rod having a threaded portion 88 extending through a sleeve 89 of a trunnion block 90 rockably mounted on or in a rigid arm projection 91 of the bracket 80. Upper and lower adjusting nuts 92 and 93 mounted on the threaded portion 88 and engageable with the ends of the trunnion sleeve 89 provide for actuation of the link 87 in opposite directions for producing the roll-adjusting swinging movement of the lever 86.

The co-operating rolls 72 and 73 can be mounted directly on the drawing die slide 22 or, if desired, the second slide 70 can be suitably attached to the drawing slide. Preferably, however, the second slide 70 is mounted in the guideway 21 more or less independently of the drawing slide 22 and is actuatable through a working stroke by being pushed over and along the wire 11 while the latter is being held against backward movement by the grip device 24. The working stroke of the shaping device 12 is imparted thereto by the draw lever 23 through the drawing slide 22, that is, the second slide 70 is pushed over and along the wire 11 by the drawing slide 22 during the drawing stroke of the latter. For this purpose the lateral projections 71 of the drawing slide 22 are engageable with the adjacent ends of the lateral projections 71 of the second slide 70 as shown in FIG. 2. The return movement of the shaping device 12 is imparted thereto by the wire 11 when the latter is advanced, as explained above, by the action of the feed rolls 15 and 16.

The drawing die 13 is provided with an orifice 95 of a cross-sectional shape suitable for, or corresponding substantially with, the cross-sectional shape imparted to the wire 11 by the rolls of the shaping device 12. In FIG. 6 of the drawings the flattened shape of the wire, imparted

thereto by the co-operating rolls 72 and 73, is shown in cross-section and in FIG. 7 of the drawings the corresponding noncircular cross-sectional shape of the orifice 95 of the drawing die 13 is shown. The corresponding noncircular shape of the die orifice 95 is achieved by providing the die 13 with a flat wall portion or chord segment on the side thereof corresponding with the location of the flat 96 on the wire. The drawing operation performed on the wire by the die 13 reduces the cross-sectional size of the wire so that the drawn wire 11^a, although of a smaller cross-sectional size than the portion of the wire entering the die orifice, is still of a noncircular or flattened shape.

FIG. 8 of the drawings shows the cross-sectional shape of the passage of the grip device 24 as provided by the cooperating gripping portions of the grip blocks 25 and 26. As shown in FIG. 8, the gripping portion of the upper grip block 25 is a flat portion 98 and the gripping portion of the lower grip block 26 is a grooved portion 99. The flat portion 98 of the upper grip block 25 engages the flat 96 of the drawn wire 11^a and the semicircular lower portion of the wire is received in the grooved gripping portion 99 of the lower grip block 26.

FIG. 9 of the drawings shows the adjacent portions of the co-operating feed rolls 15 and 16 and the manner in which they engage the drawn wire 11^a. The upper feed roll 15 has a flat or cylindrical peripheral surface 101 which engages the flat 96 of the drawn wire 11^a, and the lower feed roll 16 has a concave peripheral groove 102 in which the semicircular lower portion or segment of the drawn wire is received.

From the construction of the wire drawing machine 10 and the relative arrangement of the components thereof as above described, it will be observed that the grip device 24, the drawing die 13 and the shaping device 12 are located in a relatively closely spaced relation longitudinally of the machine and along the axis of the wire 11. The feed device 17 and the fabricating machine 14 are also located relatively close to the grip device 24. With the various components just referred to located in such a relatively closely spaced relation, the portions of the wire 11 extending between these components are relatively short sections in which only a very small amount of twist, if any, will occur notwithstanding the fact that wire of a noncircular cross-section has a strong inherent tendency to assume a twisted form. Since the twist occurring in the wire 11 as operated upon by the machine 10 and supplied to the header 14 will be extremely small or negligible in amount, error and difficulties heretofore encountered in the functioning of the dies of such a header on account of such twist will be overcome and avoided. It will also be seen that when the shaping of the wire 11 by the device 12 is accomplished with such device located on the entry side of the drawing die 13, any marring or irregularity produced in the wire by the shaping operation will be removed by the drawing die during the drawing operation. In view of the advantages and novel functioning of the wire drawing machine 10 as hereinabove described, it will be understood also that this invention provides for the delivery of drawn wire of a desired accurate size and cross-sectional shape to the associated fabricating machine or header and that this is accomplished in a smooth, efficient and satisfactory manner even though the wire being processed is relatively small-size or fine wire.

Although the wire drawing apparatus of this invention has been illustrated and described herein to a somewhat detailed extent it will be understood, of course, that the invention is not to be regarded as being limited correspondingly in scope but includes all changes and modifications coming within the terms of the claims hereof.

Having described my invention, I claim:

1. In wire drawing apparatus, the combination with a reciprocable slide carrying a drawing die and movable by swingable lever means through a drawing stroke in a

direction along a wire held against backward movement by a grip device, of a flattening device movable along the wire by said slide and comprising co-operating pressure rolls effective on the wire to flatten the same, said flattening device being located on the entry side of said drawing die for flattening the wire prior to the drawing thereof, said die having an orifice defined in part by a flat portion on the die to co-operate with the flat portion formed on the wire by said rolls.

10 2. Wire drawing apparatus as defined in claim 1 wherein in said flattening device comprises a second slide adjacent the first-mentioned slide and said co-operating rolls comprise a grooved roll engaging one side of the wire and a transversely flat roll engaging the other side thereof.

15 3. In a wire drawing machine the combination of a frame structure having a guideway, slide means movable in said guideway, a grip device on said frame structure for gripping a wire being drawn, a drawing die on said slide means for movement therewith through a drawing stroke over and along the wire in a direction away from said grip device, actuating means effective on said slide means for producing said drawing stroke, and shaping rolls rotatably mounted on said slide means and having co-operating portions defining a bight passage of noncircular cross-section and effective on the wire for pressure-shaping the same to the cross-sectional shape of said passage, said rolls being movable over and along the wire in shaping engagement therewith during said drawing stroke.

20 4. A wire drawing machine as defined in claim 3 wherein in said slide means comprises a first slide carrying said die, and a second slide carrying said rolls and being movable along said guideway by pushing engagement of said first slide therewith.

25 5. In wire drawing apparatus, the combination with a reciprocable slide carrying a drawing die and movable by swingable lever means through a drawing stroke in a direction along a wire held against backward movement by a grip device, of a shaping device movable along the wire by said slide and comprising co-operating pressure rolls effective on the wire to flatten the same by rolling, means supporting one of said rolls for rotation, and eccentric means supporting the other rolls for free rotation and providing for adjustment of the position thereof for varying the pressure of said rolls on the wire.

30 6. In wire drawing apparatus, the combination with a reciprocable slide carrying a drawing die and movable by swingable lever means through a drawing stroke in a direction along a wire held against backward movement by a grip device, of a shaping device movable along the wire by said slide and comprising co-operating pressure rolls defining a bight passage and effective on the wire to shape the same in said passage, one of said rolls being a relatively small-diameter shaping roll and the other being a peripherally grooved relatively large-diameter support roll, means supporting said one roll for free rotation, eccentric means supporting said other roll for free rotation, and adjusting means effective to rotate said eccentric means for varying the position of said other roll relative to said one roll for varying the size of said passage.

35 7. In a wire drawing machine a frame structure having a guideway, a first slide movable in said guideway, a grip device on said frame structure for gripping a wire being drawn, a drawing die having a drawing orifice including a noncircular portion, said die being mounted on said first slide and movable therewith through a drawing stroke along the wire in a direction away from said grip device, actuating means effective on said first slide for producing said drawing stroke, a second slide movable in said guideway and through a work stroke by a pushing engagement of said first slide thereagainst, a pair of wire-shaping rolls having co-operating portions defining a noncircular bight passage and effective on the wire for shaping the same by rolling to the noncircular shape of

40 85 said passage during said work stroke to correspond with

the noncircular drawing orifice of said die, and pivot shaft means on said second slide supporting said rolls for free rotation and including eccentric means rotatably adjustable for varying the pressure position of one of said rolls relative to the other.

8. A wire drawing machine as defined in claim 7 wherein in said grip device, drawing die and pair of rolls are in a relatively closely spaced relation along the axis of said wire for minimizing the occurrence of twist in the latter.

9. A wire drawing machine as defined in claim 7 wherein in said second slide is located on the side of said first slide remote from said grip device and said rolls comprise a wire flattening device, one of said rolls being a relatively small-diameter cylindrical work roll and the other being a peripherally grooved relatively large-diameter support roll.

10. A wire drawing machine as defined in claim 9 wherein said pressure roll is an upper roll and said support roll is a lower roll, and wherein said grip device comprises co-operating upper and lower grip blocks, said lower roll and lower block each having a wire-receiving groove therein for receiving the lower portion of the wire and said upper roll and upper block each having a transversely flat portion engageable with the flat portion of the wire.

11. The method of shaping and drawing wire by cold working for direct feeding to a fabricating machine substantially without twist; comprising the steps of intermittently advancing the wire in a forward direction toward the fabricating machine and along a path of feed movement extending in succession through a shaping means, a drawing means and a gripping means located in a relatively closely spaced relation along said path; gripping a portion of the wire which has already been shaped and

5 drawn to prevent backward movement of the wire; and shaping the wire as to cross-section, and drawing the shaped wire to a similar but smaller cross-section, by pushing the shaping means and the drawing means conjointly and in a tandem relation over portions of the wire, which are spaced in the backward direction from the gripping means, while the wire is being thus held from backward movement by said gripping means.

12. The method defined in claim 11 wherein the shaping of the wire comprises flattening the same by squeezing thereof between a grooved support roll located on one side of the wire and a cylindrical work roll in flattening engagement with the opposite side of the wire and wherein the drawing of the wire immediately follows the shaping thereof and is carried out by a drawing die whose orifice has a flat side acting on the flattened side of the shaped wire.
